UNITED STATES PATENT OFFICE.

DAVID F. STAMBAUGH, OF EFFINGHAM, ILLINOIS.

SPRING BED-BOTTOM.

SPECIFICATION forming part of Letters Patent No. 297,868, dated April 29, 1884.

Application filed May 7, 1883. (No model.)

To all whom it may concern:

Be it known that I, DAVID F. STAMBAUGH, a citizen of the United States, residing at Effingham, in the county of Effingham and State 5 of Illinois, have invented certain new and useful Improvements in Bed-Bottoms; and I do hereby declare the following to be a full, clear, and exact description of the invention, such as will enable others skilled in the art to which 10 it appertains to make and use the same.

This invention relates to certain improvements in spring bed-bottoms; and it has for its objects to provide a spring bed-bottom that will be cheap and simple in construction, and 15 which will accommodate itself to the weight of the occupant, as more fully hereinafter specified. These objects I attain by the means illustrated in the accompanying drawings, in which—

20 Figure 1 represents a partial plan view of my improved bed-bottom, and Fig. 2 a longitudinal vertical sectional view thereof.

In the drawings, the letter A indicates a 25 rectangular frame, the transverse end bars of which are set at an angle, as shown in Fig. 2 of the drawings. About midway between the ends of the longitudinal rails B are secured the transverse slats C, upon which are secured the spiral springs D, which support the longitudinal slats E. The springs at their tops are 30 connected together by means of links E', the springs at each side being connected to the side slats by means of suitable clips, F. The longitudinal slats are connected to each other 35 by means of the cords G, and the springs are

connected to the cords by lateral extensions H, as indicated by dotted lines in Fig. 1 of the drawings. The said longitudinal slats at their ends are connected to the end rails of the frame A by means of spiral springs I, secured 40 to the frame by screws or otherwise, as indicated. The spiral springs are connected at their tops by means of links B'.

It will be seen that as constructed when the occupant's weight is light the tendency will be 45 to depress the upright spiral springs below the slats; but as the weight increases the tendency will be to draw upon the end springs, thus causing the bed to automatically adjust itself to the weight of the occupant.

Having thus described my invention, what 50 I claim, and desire to secure by Letters Patent, is—

The combination, in a bed-bottom of a rectangular frame provided with a series of cross-slats, C, a series of spiral springs, D, located thereon, the links B', connecting the upper ends of the springs, the longitudinal slats H, secured to said springs, the cords G, connecting the slats, and the longitudinal spiral 55 springs I, connecting the slats at the ends to the frame, substantially as and for the purposes specified.

In testimony whereof I affix my signature in presence of two witnesses.

D. F. STAMBAUGH.
